UNITED STATES PATENT OFFICE.

JACOB A. HYLE AND GEORGE W. WHITEMAN, OF PHILADELPHIA, PENNSYLVANIA.

RAILWAY RAIL JOINT.

1,418,930.

Specification of Letters Patent. Patented June 6, 1922.

Application filed October 20, 1921. Serial No. 509,107.

To all whom it may concern:

Be it known that we, JACOB A. HYLE and GEORGE W. WHITEMAN, citizens of the United States, residing at Philadelphia, in the county of Philadelphia and State of Pennsylvania, have invented certain new and useful Improvements in Railway Rail Joints, of which the following is a specification.

10 This invention relates to an improvement in railway rail joints, and has special reference to a novel construction of the rail joint bars or plates, whereby the clamping effect against the track rails at and near the meeting ends of the rails is materially and practically improved and adapted to compensate for the wear which usually occurs at and near said meeting ends, and this invention is an improvement on the patent granted to 20 Jacob A. Hyle, under date of August 23, 1921, No. 1,388,184.

The main object of the invention is to provide novel, durable, economical, simple and thoroughly effective means for safely and reliably uniting and securing the meeting ends of railroad track rails together, said means being adapted to materially increase the longevity of the rail joint and the rails.

A further object is to provide a safe, 30 strong and reliable railway rail joint composed of few parts, with means for safely and firmly securing the parts together when properly assembled, said joint including means adapted to compensate for the wear 35 which customarily takes place at and near the juncture of the meeting ends of the track rails.

Another object of this invention is to so construct our improved rail joint that the 40 meeting ends of the track rails will possess a maximum of vertical strength, together with a maximum of lateral strength and rigidity to withstand the excessive strain to which the rails are subjected by the travel 45 of the heavy rolling stock thereon.

Further objects of the invention are to so construct each rail joint bar or plate that if broken it will be impossible for the broken 50 parts of said bar or plate to work outwardly and thus become dangerous during the travel of the rolling stock thereover; to so construct each rail joint bar or plate that its outer vertical face will be clamped by a wedge-shaped member throughout its 55 length; that the upper reinforced portion

of each bar or plate will be caused to be flexed against the lower surface of the tread and the upper end portion of the web of the rail as the wear takes place at and near the juncture of the rails, by the proper adjustment of the wedge-shaped member fitted therein and simultaneously cause the lower reinforced portion of said joint bars to firmly and securely clamp the base of each rail and the lower portion of the rail web; 60 to construct each bar or plate from a single piece of metal formed with an excess of metal at its head and foot portions, and thickened at that portion adapted to contact with the rail where the tread merges 65 into the web and where the web merges into the base, and a comparatively thin intermediate portion connecting said head and foot portions adapted to yield when the wedge member is forced or drawn inwardly 70 thereby causing the said bars or plates to fit snugly and securely against the web, tread 75 and base of each rail.

The foregoing and such other objects as may appear from the ensuing description 80 are attained by the construction, arrangement, combination and location of the parts hereinafter more fully described, illustrated in the accompanying drawings, and particularly pointed out in the claims appended 85 hereto, it being understood that slight changes in the precise form, proportions and minor details of the construction may be resorted to without departing from the spirit 90 or sacrificing any of the advantages of the invention.

In the accompanying drawings which form a part of the specification it will be seen that:—

Figure 1 is a perspective of the improved rail joint embodying our invention, adapted to be secured to the railway ties.

Fig. 2 is a sectional elevation, showing the base of the rail resting on a tie plate, and a side elevation of a portion of a securing spike on the outer side of the rail.

Fig. 3 is a sectional elevation of a slightly modified form.

Fig. 4 is a side elevation of the joint bar or plate shown in Figs. 1 and 2, disconnected 105 from the joint.

Fig. 5 is a side elevation of the wedge-member removed from the joint.

Fig. 6 is a side elevation of the joint bar or plate shown in Fig. 3.

Fig. 7 is an end view of the bar or plate shown in Figure 6, and

Fig. 8 is an end view of the bar or plate shown in Fig. 4.

5 Similar numerals of reference are employed to designate corresponding parts throughout the several figures of the drawings.

In the embodiment of our invention as 10 illustrated, it will be observed by reference to Fig. 1 that the track rails 1 and 2 are shown as being connected together by the joint bars or plates 3, each of said bars or plates being preferably rolled from a single 15 piece of steel and formed with a central elongated opening 4 formed therethrough; an upper head member 5, said member being formed with an excess of metal thickened or enlarged at 6, to furnish the desired 20 strength, and is so shaped as to fit snugly and closely against and clamp the under surface of the rail tread and the upper portion of the web of the rail, and the foot or lowermost member 7 of said joint bar or plate is 25 also formed with an excess of metal thickened or reinforced at 8 and so shaped as to contact with and clamp the upper surface of the base of the rail and the lowermost portion of the web of the track rail, the web 30 portion 9 of said joint bar or plate being rolled comparatively thin for the purpose hereinafter described.

By reference to Fig. 2 it will be seen that 35 the base of the rail is seated upon the well known tie or base plate 10 which is provided with an integral upward extension 11, adapted to contact with the outer side of the rail base and thus retain the rail in its proper alignment at all times, side plate 10 being 40 provided with suitable openings therethrough adapted to receive an ordinary railway spike, such as 12, which is driven through the recessed opening 13 formed in the outer edge of the joint bar or plate and 45 into a railway tie (not shown), with the head of the securing spike overlapping the upper surface of the bar or plate 3 for securing said rail and bar or plate to the railway ties.

50 It will be perceived that the outer face of each joint bar or plate 3 forms a wedge-shaped recess 14 for the reception of a wedge-shaped member 15 which is fitted within said recess overlapping the web portion 9 of bar or plate 3, and extending throughout the length of the said bar. Each wedge-shaped member is provided with four central openings for the reception of the securing bolts 16, each bolt being passed 55 through the track rail, and each bolt nearest the end of the joint is passed through an opening formed through the web of the joint bars near each end thereof, while the intermediate bolts pass through the elongated openings 4 in said joint bars, all of the se-

curing bolts passing through the joint bars and wedge-members, and securely fitted to the threaded end of each bolt is a securing nut 17 adapted to contact with the outer face of the wedge members, said nuts being fitted 70 so as to alternate on opposite sides of the joint.

It will be readily evident that when the joint wears at and near the meeting ends of the rails by drawing the nuts inwardly 75 on the two bolts nearest said meeting ends the wedge-members are gradually forced inward into the recess 14 thus forcing the joint bar to yield in its thinnest web portion and causing said bars to be moved in closer 80 contact with the web of the rails and more directly between the top and bottom thereof and simultaneously causing the heavy head and foot members of the joint bars to be flexed into rigid contact with the lower surface of the rail treads and the upper surface of the rail bases, respectively. Thus more direct strength is attained than when the joint bars are away from the rails, and as expansion and contraction cause wear the 90 joint bars may be drawn closer to the rails from time to time as the wear permits at and near their meeting ends, while the clamping effect of the bars is not so intense at and near the ends thereof, where the 95 clamping of the ordinary rail joint becomes most effective after wear. Hence the wave motion of the track rails usually produced by the movement of the rolling stock thereon may pass through the joint to the rail ends, 100 thereby eliminating the tendency of the breakage of the rail in a plane with one or more of the bolt holes formed near the meeting ends of the rails, thus saving annually a considerable amount to the railway system. 105

It will be seen that the heavy wedge-members adjustably fitted within the recess 14 of each joint bar 3 constitute sufficient material to form an unusually strong, durable and efficient joint, which may be easily and readily adjusted and kept tight at the required and desired points and is much easier to adjust and tighten than the ordinary rail joint usually employed.

It is a well known fact that in the event 115 of breakage of joints of this general type it usually occurs vertically through the joint bars or plates at or near the bolt holes, and owing to the excessive shaking and jarring caused by the passing of the rolling stock, 120 both the upper and lower portions of the joint bar or plate are liable to work outwardly thus causing a dangerous obstruction, hence to prevent such dangers. We thicken, enlarge or reinforce each joint plate 125 at the points 6 and 8, thus forming a dovetail like portion between the points 6 and 8 and the outer side of the joint bar which, together with the clamping effect of the wedge-members with the outer face of the 130

web portion of the joint bars renders it impossible for the broken portions of said bars to work outwardly.

By our improved construction of rail joint 5 the battering of the ends of the rails is entirely avoided by forcing the wedge-members inwardly at and near their central portion, thereby spreading, flexing or bowing upwardly such portions of the joint bars as 10 are disposed at and near the meeting ends of the rails into close and rigid contact with the worn portions of the rails, thus lessening the clamping effect at and near the outer ends of the joint and permitting the wave 15 motion to the rail to continue to the bowed portion of the joint bars, which is substantially at the end of the track rail, thereby preventing the usual tendency of the breakage of the rail at one or the other of the bolt 20 holes near its ends.

It will also be evident that the forcing of the wedge-members inwardly at and near their central portions will insure tight nuts at the end portions of the joint, and that 25 this construction of joint may be used with or without the use of railway joint cross-ties.

It will be understood that the elongated opening 4 formed in the central portion of 30 each joint bar or plate 3, may be contracted or restricted to any suitable or desirable degree, it being evident that by the formation of said elongated opening through the central portion of each joint bar or plate the 35 head and foot portions thereof may be more readily forced or expanded upwardly and downwardly, and caused to clamp tightly against the head and base portions of the rails, respectively, when the central securing 40 bolts are forced inwardly by tightening the securing nuts.

Having thus described our invention what we claim and desire to secure by Letters Patent is:—

45 1. A rail joint of the character described, comprising track rails, a splice bar having an excess of metal at its lower and upper portions and a thickened portion at the inner curved end of said lower and upper portions with a recess formed within its outer face, and a thin web member, and means fitted within said recess for causing said lower and upper portions to be flexed against the rail tread and a portion of the rail web.

55 2. A rail joint of the character described, comprising track rails, a splice bar having outwardly extending head and foot portions formed of an excess of metal in dovetail form and with a recess formed within its outer face and a thin web member, and means fitted within said recess for causing said head portion to be bowed upwardly at and near its central portion into tight contact with the under surface of the rail tread.

3. A rail joint of the character described, 65 comprising track rails, a splice bar formed with an excess of metal at its upper and lower portions, each of said portions forming an outwardly extended dovetail between the track rail and a wedge-member, and a 70 recess formed within the outer face of said splice bar, a thin yielding web member, and a wedge-member adapted to cause said upper and lower portions to be flexed into contact with the tread, base and web portions 75 of the rails.

4. A rail joint of the character described, comprising track rails, a splice bar having outwardly extended head and foot portions formed of an excess of metal thickened at its 80 inner side portion with a recess formed within its outer face and a thin web portion connecting said head and foot portions, and means fitted within said recess for causing said head and foot portions to be flexed 85 tightly into contact with the tread and base portions of the rails.

5. A rail joint of the character described, comprising track rails, a splice bar having outwardly extended head and foot portions 90 formed of an excess of metal with a thickened portion at the point of contact with the tread and web of the rails, with a recess formed within its outer face and a thin web portion connecting said head and foot portions, and means fitted within said recess for causing said head portion to be bowed 95 tightly into contact with the lower surface of the rail treads at all times.

6. A rail joint of the character described, 100 comprising track rails, a splice bar having outwardly extended head and foot portions, each of said portions being thickened at its inner side, each splice bar being formed with a recessed outer face, a thin yielding web connecting said head and foot members with an elongated opening formed through the central portion of said web, and means fitted within said recess for flexing said head and foot portions tightly into contact 105 with the tread, base and web of the rails.

7. A rail joint of the character described, comprising track rails, a splice bar formed with outwardly extending head and foot portions having an excess of metal and a 115 thickened portion at the inner side of each head and foot portion with a recess formed within its outer face, a thin yielding web connecting said head and foot portions and an elongated opening formed through the central portion of said web, and means fitted within said recess for flexing said head portion upwardly at and near the center of said splice bar into tight contact with the lower surface of the tread of the rails.
